AIRPLANE

Vincent J. Burnelli, Keyport, N. J., assignor to
Burnelli Aircraft, Ltd., a corporation of Delaware

Application February 19, 1935, Serial No. 7,274

3 Claims. (Cl. 244—12)

In military aircraft, such for example as bombers, it is desirable that gun fire from rear cockpits may have a horizontal range through at least 180° and a commensurate vertical firing range, for the complete rear protection of the aircraft.

5 This feature is emphasized in the present application for a multi-engined bombing airplane of the Burnelli all-wing type.

My invention comprises these features:—

10 The provision of booms extending rearwardly, in spaced relation, from the supporting element, and carrying the empennage, said booms each having a gunner's cockpit, which is in communication with the fuselage interior, so that the gunners can pass between said cockpits and fuselage.

15 Also I provide in this structure a horizontal stabilizer, spanned between the booms and supporting a single vertical stabilizer, with a vertical rudder, and a tail wheel, which may be retractable, that is pendent from said horizontal stabilizer, below said vertical stabilizer.

20 Other features and advantages of my invention will hereinafter appear.

In the drawings:—

25 Figure 1 is a top plan view of my improved bombing airplane.

Fig. 2 is a front view thereof.

Fig. 3 is a side elevation, partly in vertical section.

30 Fig. 4 is an enlarged plan view, broken away and partly in horizontal section of the central portion of the airplane.

Fig. 5 is an enlarged sectional detail view of the empennage and tail wheel.

35 Fig. 6 is a bottom plan view of Fig. 5, and

Fig. 7 is a front elevation thereof.

In said views the supporting element is shown as having the central wing section 1 and the respective lateral wing sections 2. As known in this 40 Burnelli all-wing type of airplane the upper surface of the entire wing is of substantially unobstructed airfoil contour, this also being true of the wing under surface excepting that the central section 1 is deeper than the lateral sections, thereby providing the side walls 3 for the lower portion of said central section.

A pair of engine mounts 4 containing engines that are provided with propellers 5 are shown as projecting forwardly from the leading edge of 50 wing section 1, and a pilots' cockpit portion 6 extends forwardly from the same leading edge, between the engine mounts, said portion 6 being further extended forwardly to provide accommodation, indicated at 7, for a forward gunner.

55 Booms 8 are shown as extending rearwardly

from the central wing section 1, said booms being spaced apart and merging with said central section in faired fashion, as at 9, into the upper surface of said central section. Said booms may, as indicated, be hollow and tapered rearwardly, and they are each provided with a gunner's cockpit 10, it being an essential feature of my invention that means of communication are provided between the interior of each cockpit and the interior of the central wing section.

5 The means of intercommunication between the cockpits 10 and fuselage interior are here indicated by clearances 11 provided through the upper surface of the central wing section at those portions thereof which lie within the hollow booms 8, where such booms have their merged relation with wing section 1. Gunners may easily pass through these clearances and thus enter or leave the cockpits when passing from or to the interior of the wing.

10 The usual pilots' cockpit is shown at 12, and retractable landing gear at 13.

As will be noted in Fig. 4, bomb holding compartments are indicated at 14, fuel tanks at 15 and a rear compartment at 16.

15 The arrows in Fig. 4 indicate passageways that lead between the wing interior, the pilots' cockpit and the gunners' rear cockpits.

The booms 8, which are required to be hollow at their portions extending forwardly of the cockpits 10, or at least to have passageways that communicate between said cockpits and the wing interior, may or may not be hollow in their rearward extension, provided said booms possess the necessary qualifications for carrying the tail group or empennage.

20 Thus said tail group is composed of a horizontal stabilizer 17 which is spanned between and carried by booms 8 at their outer ends and the elevator 18 is hinged to said stabilizer in the usual manner. A single vertical stabilizer 19 is mounted on stabilizer 17, aided by the reinforcement of struts 20, and a vertical rudder 21 is hinged to stabilizer 19. A retractable tail wheel 22 is shown as extended dependingly from the horizontal stabilizer, centrally thereof, to lie directly beneath the vertical stabilizer, and thus to profit by the reinforcement accorded said vertical stabilizer in resisting the landing shocks to which the tail wheel may be subjected.

25 Fairing is provided by a stream-lined apron 23 that is pendent from the stabilizer 17, and provided with a slot 24 for the passage of the tail wheel into and out of said apron.

The dot-and-dash lines on Fig. 1 serve to illus- 55

trate the range of gun fire available from the rear cockpits and it should be noted that the use of a single vertical stabilizer in its centrally disposed rearward position provides a minimum of 5 interference in the firing field, as will be clearly apparent.

Variations within the spirit and scope of my invention are equally comprehended by the foregoing disclosure.

10 I claim:

1. An airplane having a lift producing airfoil-shaped body portion with an enclosed space therein, a pair of empennage carrying booms extending rearwardly from said body portion, one 15 at each side thereof, a gunner's cockpit located at the junction of each boom with the body portion, horizontal control surfaces carried by said booms, and vertical control surfaces supported upon said horizontal control surfaces midway between said booms whereby there will be an unobstructed range of fire from each gunner's cockpit in excess of ninety degrees.

2. An airplane having a lift producing airfoil-shaped body portion with an enclosed space there- 20 in, a pair of empennage carrying booms extend-

ing rearwardly from said body portion, one at each side thereof, a gunner's cockpit located at the junction of each boom with the body portion and being partly located in the boom and partly in the body portion, horizontal control surfaces carried by said booms, and vertical control surfaces supported upon said horizontal control surfaces midway between said booms whereby there will be an unobstructed range of fire from each gunner's cockpit in excess of ninety degrees. 5

3. An airplane having a lift producing airfoil-shaped body portion with an enclosed space therein, a pair of empennage carrying booms extending rearwardly from said body portion, one 15 at each side thereof, a gunner's cockpit located at the junction of each boom with the body portion, means of communication between each cockpit and the enclosed space within said body portion, horizontal control surfaces carried by said booms, and vertical control surfaces sup- 20 ported upon said horizontal control surfaces midway between said booms whereby there will be an unobstructed range of fire from each gunner's cockpit in excess of ninety degrees.

VINCENT J. BURNELLI. 25
